Fig. 1

Fig. 2

FIG. 1 is a perspective view of a building complex showing my new design; and

FIG. 2 is a top plan view of the building complex illustrated in FIG. 1.

The opposite side of the building complex not apparent in FIG. 1 is the same in appearance as the side illustrated.

The characteristic feature of my design resides in the provision of a central rectangular building with tower-like building structures located at the four corners thereof.

This is a divisional application of design application Ser. No. 12,830, filed by the same applicant on July 19, 1968.

I claim:

The ornamental design for a building complex, substantially as shown and described.
